UNITED STATES PATENT OFFICE.

PETER BARLOW, OF ROCHESTER, MINNESOTA.

SNOW SKATE.

Application filed May 31, 1921. Serial No. 473,719.

To all whom it may concern:

Be it known that I, PETER BARLOW, a citizen of the United States, residing at Rochester, in the county of Olmsted and 5 State of Minnesota, have invented certain new and useful Improvements in Snow Skates; and I do declare the following to be a full, clear, and exact description of the invention, such as will enable others 10 skilled in the art to which it appertains to make and use the same.

This invention relates broadly to improvements in skates, having particular reference to a device of this class which embodies a relatively long and wide runner 15 which is designed particularly for skating on snow and ice covered surfaces.

The principal object of the invention is to generally improve upon skates of this class 20 by the provision of one of extreme simplicity and durability, which is light in weight, easy to attach and detach, well balanced to prevent it from tilting and throwing the wearer and advantageous and effective in 25 many other respects as will appear by reading the following description.

Another and very important object of the invention is to provide a skate which embodies a runner with a pair of independent 30 foot supports which are longitudinally shiftable along the upper face of the runner to position them for effectively supporting shoes of varying lengths.

Another object of the invention is to provide a skate wherein the foot supports include heel and toe plates which are spaced sufficiently far above the upper face of the runner to clear the upper surface of snow of considerable depth there being no unnecessary obstructions between the plates and runner and this being advantageous in that it permits the snow to pass between the plates and runner so as not to resist free gliding on the snow or ice as the case may be.

45 Other objects and advantages of the invention will become apparent during the course of the following description.

In the accompanying drawing forming a part of this specification and in which like 50 numerals are employed to designate like parts throughout the same:

Figure 1 is a top plan view of a skate constructed in accordance with this invention.

55 Figure 2 is a side elevational view thereof with portions of the runner broken away

and shown in section to disclose the construction and arrangement of parts more clearly.

Figure 3 is a bottom plan view with the intermediate portion of the metallic part of 60 the runner broken away to disclose the anchoring plates for the threaded ends of the retaining bolts.

Figure 4 is a cross sectional view taken substantially on the plane of the line 4-4 65 of Fig. 2.

Referring to the drawing in detail, the numeral 1 designates generally a runner which in the preferred form is made up of a relatively long wooden strip or bar 2 which 70 has its forward end upturned as indicated at 3. Secured by screws or other suitable fastenings to the lower face of the wooden bar 2 near the opposite end of the latter is a metal strip 4 which constitutes the running surface, that is the portion which directly rides on the ice or snow. At longitudinally spaced points, the bar 2 is provided with a plurality of vertical bolt-holes 5 which serve a purpose to be hereinafter 75 described. The bar 2 in addition to being provided with these bolt-holes, is provided in its under face with longitudinally spaced recesses in which metal plates 6 are secured in any suitable way. It may be stated here 80 that these plates 6 are flush with the bottom face of the bar 2 and are equipped with spaced rows of longitudinally spaced screw-threaded holes 7 which are disposed in alignment with the aforesaid bolt-holes 5. 85 The aforesaid metallic strip 4 covers these plates as shown.

As before indicated, the skate in addition to embodying the runner, includes a heel and toe support which are designated 95 respectively by the numerals 8 and 9, these supports being longitudinally shiftable along the upper face of the bar 2 to accommodate shoes of varying lengths. While these supports may be constructed otherwise, 100 I prefer that they each include plates 10 shaped to accommodate the part of the shoe with which they contact, these plates having secured thereto in any suitable way, two-part depending legs 11 which are secured to 105 the plates near the opposite ends of the latter. As before pointed out, these legs are sufficiently high to space the plates a considerable distance above the upper face of the runner to permit snow and ice to 110 pass between the plates and runner without forming a resistance and retarding the

2
speed of the skate. Also, by positioning the plates at this elevation, there is less liability of the shoe digging into fairly deep snows as would otherwise occur. The height of 5 the supports will permit the shoes to clear the surface of the snow. Referring again to the legs 11, it will be seen that the parts of which each is made have their lower ends directed laterally as indicated at 12 and 10 these laterally directed ends are apertured to permit passage of bolts 13 therethrough, these bolts passing downwardly through the aforesaid bolt-holes 5 and having their lower threaded ends engaged with the 15 threads of the apertures 7 as shown. It is yet to be pointed out that suitable clamps 14 are carried by the plates 10 for engagement with the sole of the shoe. These clamps, of course, are adjustable to accommodate 20 different widths of shoes.

A skate constructed in accordance with the foregoing description will be advantageous in that by simply removing the bolts 13, it will be possible to shift the heel and 25 toe supporting devices toward or from each other to accommodate shoes of different lengths. When the desired points of adjustments are obtained, the bolts are replaced in the adjacent or desired bolt-holes 30 to retain the devices in set positions. The metallic part 4 of the runner is detachably connected with wooden portion thereof and whenever it is badly worn, it can be readily removed and replaced with a new strip. As 35 before indicated, the skate shown is well

balanced and there is little or no liability of the same accidentally tilting and throwing the wearer. A skate of the type shown has a relatively large surface for bearing on the snow and ice and it thus can be used 40 by children in place of sleighs, owing to the wide surface which enables a child to remain on his feet, as is not usually possible with the narrow runners such as are used on the common ice skates now patented and 45 marketed. The several features and advantages of the invention and manner of making use thereof have, no doubt, become apparent from the foregoing description and drawing. In view of this, a more lengthy 50 description is thought unnecessary.

If desired, slight minor changes coming within the scope of the subjoined claim may be resorted to as is understood.

I claim:

A skate of the class described comprising a runner, having a plurality of vertical longitudinally alined bolt-holes, plates secured to the under face of said runner, having rows of alined screw-threaded holes alined with said bolt-holes, foot supports shiftable along the upper face of the runner, and retaining bolts carried by said supports, said bolts extending through the bolt holes and having their lower threaded ends engaged 60 with the threaded holes in said plates.

In testimony whereof I have hereunto set my hand.

PETER BARLOW.
